(57) **CLAIM**

The ornamental design for an electrical plug with fuse, as shown and described.

DESCRIPTION

FIG. 1 is a top-front-left perspective view of an electrical plug with fuse showing our new design;

FIG. 2 is a bottom-rear-right perspective view thereof;

FIG. 3 is a left side elevation thereof;

FIG. 4 is a right side elevation thereof;

FIG. 5 is a rear elevation thereof;

FIG. 6 is a front elevation thereof;

FIG. 7 is a top plan view thereof; and,

FIG. 8 is a bottom plan view thereof.

1 Claim, 3 Drawing Sheets
